CLAIM

I claim the ornamental design for a heart-shaped pendant with reverse side having concealed alarm transmitter, as shown and described.

DESCRIPTION

FIG. 1 is a top, side and rear perspective view of a heart-shaped pendant with reverse side having concealed alarm transmitter showing my new design;

FIG. 2 is a rear elevational view thereof;

FIG. 3 is a top plan view thereof;

FIG. 4 is a side elevational view thereof, the elevational view of the opposing side being a mirror image thereof;

FIG. 5 is a bottom plan view thereof;

FIG. 6 is a front elevational view thereof; and,

FIG. 7 is a top, side and front perspective view showing the heart-shaped pendant with reverse side having concealed alarm transmitter in use; the broken lines depict environmental structure for illustrative purposes only and form no part of the claimed design.
